UNITED STATES PATENT OFFICE.

ROBERT DEMAS MONINGER, OF WASHINGTON, PENNSYLVANIA; ANNIE R. MONINGER
BEING ADMINISTRATOR OF SAID ROBERT DEMAS MONINGER, DECEASED.

PHOTOGRAPHIC-PRINTING APPARATUS.

1,417,403.

Specification of Letters Patent. Patented May 23, 1922.

Application filed June 25, 1920. Serial No. 391,601.

To all whom it may concern:

Be it known that I, ROBERT DEMAS MONINGER, a citizen of the United States, and a resident of Washington, in the county of Washington and State of Pennsylvania, have invented certain new and useful Improvements in Photographic-Printing Apparatus, of which the following is a specification.

10 My invention relates to improvements in photographic printing apparatus.

The object of the invention is to provide an improved photographic printing apparatus of simple and durable construction, 15 reliable in operation and adjustable to the convenience of the operator and which may be efficiently operated with the exercise of minimum skill on the part of the operator.

Other objects and advantages of the invention reside in certain novel features of construction, combination and arrangement of parts which will be hereinafter more fully described and particularly pointed out in the appended claims, reference being had to 25 the accompanying drawings forming part of this specification, and in which:

Figure 1 is a perspective view of the photographic printing apparatus associated with suitable table;

30 Figure 2 is a transverse vertical sectional view of the photographic printing apparatus;

Figure 3 is a vertical sectional view on line 3—3 of Figure 2;

Figure 4 is a fragmentary side elevational view, showing the presser in retracted position;

Figure 5 is a similar view, showing the presser in intermediate position;

40 Figure 6 is a similar view, showing the presser in extended position;

Figure 7 is a detail perspective view of the presser block, presser rollers and associated structure;

45 Figure 8 is a detail perspective view of the bracket for connecting the presser block to the presser rolls;

Figure 9 is a detail perspective view of the spring for the link connection;

50 Figure 10 is a fragmentary plan view of the means for retaining the tilttable section in adjusted position;

Figure 11 is a vertical sectional view thereof;

Figure 12 is a plan view of the print-

ing apparatus equipped with identification means; and

Figure 13 is a vertical sectional view thereof.

Referring to the drawings, it will be seen my invention contemplates a table 10 which 60 is supported upon suitable legs 11 braced by cross rails 12. The table is provided with a tilttable section 13, pivoted to the the table at 14 to swing vertically whereby the inclination of the tilttable section with respect to 65 the table may be varied as desired. The tilttable section is provided with depending side and end walls 15 and 16 respectively, and these walls together with the bottom wall 17 define a light chamber. The upper 70 surface of the tilttable section contiguous with the light chamber is provided with an opening 18. The outer surface of the side walls 15 of the tilttable section are provided with a plurality of vertically spaced slots 19 75 with which a disk 20 eccentrically pivoted as at 21, to the table 10 is adapted to selectively cooperate to thereby retain the tilttable section in adjusted position with respect to the table. It is to be understood that one 80 of such eccentrically pivoted disks cooperates with each side of the tilttable section.

A transparent support for the paper and negatives is provided and consists of a sheet of glass 22 which is seated in the tilttable section and arranged to completely cover the opening 18 of the light chamber. The top surface of the glass is coplaner with the tilttable section.

85 A presser, indicated generally at 23, is 90 adapted to coact with the transparent support to properly spread the paper and the negatives thereon to press them firmly thereagainst and provide an opaque backing during the printing operation. The presser is 95 constrained to partake of reciprocatory motion across the transparent support and cannot partake of any other except this rectilinear motion although urged into proper contact with the support. This presser comprises a pair of spaced rollers 23^a between 100 which is arranged a presser block 24 which is maintained in desired relation with respect to said rollers by means of four small brackets 25 which have their ends secured, 105 as at 26, to the respective corners of the presser block and which are provided with suitable bearings 27 for rotatably receiving

the pintles 28 of the rollers 23. A flexible band 29 of heavy dark canvas extends around the spaced rollers and the presser block. The ends of the flexible band are 5 extended through a transverse slot 30 provided therefor in the tiltable section. One end of the flexible band is rigidly secured, as at 31, to the under side of the tiltable section while the other end is resiliently secured, 10 as at 32, by means of the spring 33. The resilient securing means including the spring 33 tends to draw the band tightly around the rollers and contact block at all times and in all positions although the contact blocks and 15 rollers are freely movable relative to the flexible band.

Means are provided for reciprocating the presser across the transparent support in any position to which the tiltable section 20 may be adjusted. This means consists of a transverse shaft 34 which has its ends journaled in bearings 35 secured to the cross rails 12 of the table. Foot operating means, such as treadles 36, are mounted upon the shaft 25 34 and through a connecting rod 37 are adapted to impart a rocking movement to the bell crank 38 which has its elbow pivoted at 39. The bell crank lever includes two spaced members 40 so that the upper end 30 thereof is yoked to provide spaced arms 41. The upper end of each of these arms 41 is connected by the link 42 to the presser, having for this purpose one end pivotally connected, as at 43, to the presser block and the other end pivotally connected, as at 44, to the upper end of the arm 41.

A torsional coil spring 45 has its ends extended, as at 46, and inturned, as at 47. The inturned ends 47 are respectively seated one 40 in the arm 41 of the bell crank and the other in the link 42, as clearly shown in Figures 4, 5 and 6. This spring tends to swing the link in a counter-clockwise direction toward the arm of the bell crank lever and thereby 45 urges the presser into firm and positive contact with the support or with the tiltable section in all positions of the presser on the section.

A transverse bar 48 extends between the 50 upper arm 41 of the bell crank lever and a retractile coil spring 49 has one end secured to this bar and the opposite end secured to the table so that it serves to return the means for reciprocating the presser to normal position and thus return the presser to normal 55 retracted position.

An electric light, such as a bulb 50, is arranged in the light chamber and suitable means is provided for energizing the light. 60 This means includes a normally opened circuit closer 51 which in its normal position prevents the electric light 50 from being energized. The circuit closer 51 includes a push button 52 which is arranged in the 65 path of the transverse bar 48 so that when

the bell crank lever has been swung to move the presser to extended position, as shown in Figures 2 and 6, the bar 48 will engage the push button 52 of the circuit closer and close the circuit so that the electric light 50 70 will be energized to effect the printing.

As shown in Figures 12 and 13, identification means may be associated with the photographic printing apparatus. This identification means comprises a tape 53 75 which is arranged to feed transversely across the transparent support 22. The tape 53 bears suitable identification indicia, such as numbers, indicated as 54 which are adapted to be imprinted upon the photographs. The 80 tape is carried by a supply reel 55 and is led across the transparent support to the take up reel 56 arranged upon the opposite side thereof. The supply and take up reels are suitably mounted in rotatable bearings 85 57 and are each provided with suitable operating means, such as a knob 58. Pawl and ratchet mechanism 59 cooperate with the supply and take-up reels to control the feed of the tape. The tape bears against the top 90 surface of the transparent support and an opaque plate 60 is superposed on the table and support. The opaque plate 60 is provided with a relatively large aperture 61 to accommodate the negatives and the paper 95 and with a relatively small aperture 62 with which the identification indicia of the tape is adapted to register. Spring clips 62 are secured, as at 63, to the tiltable section and have their free ends engaging the opaque 100 plate 60 to releasably secure the plate in position.

In operation the paper and negatives are placed by the operator upon the transparent support and the treadles 36 are then depressed. This moves the presser rectilinearly from the position shown in Figure 4 through the position shown in Figure 5 to the position shown in Figure 6. In its initial movement the presser engages the 105 paper and negatives and retains them in their proper position as is indicated in Figure 5 so that any possibility of their being displaced therefrom on the transparent support is precluded. When the presser has 110 been moved to the extended position shown in Figure 6, the circuit closer has been engaged and closed by the presser bar 48 and the electric light 50 is energized to effect the printing. The operator after the desired 115 interval releases his foot from the treadle or treadles and the retractile coil spring 49 at once throws the treadles back to their normal position and moves the presser back to the retracted position shown in Figure 4. 120

An important feature of the present invention resides in the feature of adjustment of the tilting section which may be inclined to suit the convenience of the operator or the exigencies of the working conditions 125 130

and in the automatic adaptation of the presser and its actuating and retracting means to the adjustment of the tiltable section, it being noted in this respect that the link 42 while permitting the movement and accommodating the adjustment of the tiltable section is acted upon by the spring 45 to urge the presser into proper contact with the transparent support of the tilting section at all times. Again the presser does not partake of any pivotal or swinging motion but is constrained to reciprocate across the transparent support. This movement of the presser serves to prevent displacement of the paper and negatives as they are engaged by the presser in its initial movement and held thereby throughout the operation.

If the identification means shown in Figures 1, 2 and 13 is employed, the tape having been fed to proper position so that the desired identification indicia is registered with the aperture 62 of the opaque plate, the operation herein-above described may be carried out so that the negative and the identification indicia are both printed upon the paper.

As clearly shown in Figures 2 and 12, the upper surface of the tiltable section is provided with spaced transverse semi-circular grooves or depressions 64 and 65, respectively, which are adapted to receive the end rollers of the presser when the same is in extended position.

Having thus described my invention, I claim:

1. In a photographic printing apparatus of the character described, a transparent support, a presser coacting with said support and constrained to reciprocatory movement thereacross and consisting of a pair of spaced rollers, a presser block arranged between said rollers and a flexible band having its ends secured and extending around said rollers and said block and relatively movable with respect thereto, means for reciprocating said presser across said transparent support including a bell-crank lever having a yoke end and a link pivotally connecting each arm of said yoked end to the presser, and a spring for each link connection, each of said springs having one end secured to said lever and the other end secured to said link whereby said presser is urged into contact with said support in all positions.

2. In a photographic printing apparatus of the character described, a transparent support, a presser coacting with said support and constrained to reciprocatory movement thereacross and consisting of a pair of spaced rollers, a presser block arranged between said rollers and a flexible band having its ends secured and extending around said rollers and said block and relatively movable with respect thereto, means for reciprocating said presser across said trans-

parent support including a bell-crank lever having a yoke end and a link pivotally connecting each arm of said yoked end to the presser.

3. In a photographic printing apparatus of the character set forth, a table having a tiltable section and means for maintaining said tiltable section at the desired inclination with respect to said table, a transparent support carried by said tiltable section, a presser coacting with said transparent support and including a pair of spaced rollers, a presser block arranged between said rollers, and a flexible band having the ends secured and extending around said roller and said block and relatively movable with respect thereto, and means for reciprocating said presser across said transparent support.

4. In a photographic printing apparatus of the character described, a table having a tiltable section, a transparent support carried by said tiltable section, a presser coacting with said support and reciprocable thereacross, and means for reciprocating said presser including a lever, and a link connecting one arm of said lever with said presser.

5. In a photographic printing apparatus of the character described, a table having a tiltable section, a transparent support carried by said tiltable section, a presser coacting with said support and reciprocable thereacross, means for reciprocating said presser including a lever, a link connecting one arm of said lever with said presser, and a spring having one end secured to said lever and the other end secured to said link whereby said presser is urged into contact with said support in all positions.

6. In a photographic printing apparatus of the character described, a table having a tiltable section provided with a plurality of vertically spaced slots, and means for maintaining said tiltable section at the desired inclination with respect to said table including a disk eccentrically pivoted to said table and selectively engageable with the slots of said tiltable section, a transparent support carried by said tiltable section and a presser coacting with said transparent support.

7. In a photographic printing apparatus of the character described, a table having a tiltable section, a light chamber carried by said tiltable section having an opening in its upper end, a transparent support carried by the tiltable section and extending over the opening of said light chamber, an electric light in said light chamber, means for energizing said electric light including a normally open circuit closer, a presser coacting with said support and reciprocable thereacross, and means for reciprocating said presser including a lever having a yoked end and a link connecting each arm of said yoked

end to said presser, and a transverse bar carried by said yoked end and adapted in the extreme position of said presser to engage and actuate said circuit closer.

5 8. In a photographic printing apparatus of the character described, a table having a tilttable section, a light chamber carried by said tilttable section and having an opening in its upper end, a transparent support carried by

the tilttable section and extending over the 10 opening of said light chamber, an electric light in said light chamber, means for energizing said electric light including a normally opened circuit closer, a presser coacting with said support, and means for actuating said presser and for actuating said circuit closer in one position of said presser. 15

ROBERT DEMAS MONINGER.
